(57) **CLAIM**

We claim the ornamental design for a femoral broach, as shown and described.

DESCRIPTION

FIG. 1: Is a perspective view of the femoral broach showing the new, original and ornamental design;

FIG. 2: is a front view thereof;

FIG. 3: is a first side view thereof;

FIG. 4: is a back view thereof;

FIG. 5: is a second side view thereof;

FIG. 6: is a top view thereof; and,

FIG. 7: is a bottom view thereof.

The features shown in broken lines in various Figures are for illustrating reference or environmental structure.
